A. LANGDON

AUTOMATIC TRAIN CONTROL APPARATUS

Original Filed Feb. 20, 1923

Inventor:

Andrew Langdon
by Spear, Huddleston, Donaldson & Hall
Atty's.

UNITED STATES PATENT OFFICE.

ANDREW LANGDON, OF PORT JERVIS, NEW YORK, ASSIGNOR, BY MESNE ASSIGNMENTS, TO TRAIN CONTROL CORPORATION OF AMERICA, A CORPORATION OF DELAWARE.

AUTOMATIC TRAIN-CONTROL APPARATUS.

Application filed February 20, 1923, Serial No. 620,283. Renewed December 29, 1927.

In applications for Letters Patent of the United States filed by Patrick J. Clifford, April 17, 1922, No. 553,429, and Jan. 5, 1923, No. 610,879, a train stop system is described in which a primary relay on the vehicle is arranged in a conductor receiving current from the traffic rail system, due to the drop in potential between the points of contact of said conductor with the rail system.

The present invention relates to a primary relay on the vehicle for picking up current from the traffic rail system conductively, due to potential drop between the points of contact with the rail system, when the current imposed on the rail system is alternating instead of direct, said relay controlling the apparatus on the vehicle.

In the drawings:—

Figure 1 is a diagram of a track wiring which may be used in connection with the present invention.

Fig. 2 is a diagram of the present invention, which concerns particularly the primary relay on the vehicle.

The track system may be used to impose alternating current on the traffic rails in addition to that imposed for signalling purposes, but because with the present invention signals on the engine may be employed, it will be understood that the invention can be carried out, if desired, in connection with roads whereon no roadside signalling system is installed.

Referring to a track system which may be used, it will be understood by referring to Fig. 1 that when a train enters the block, its track relay T R is shunted and opened, and contact 2 closes. Then, if there is no train in the block ahead, and the relay of that block is picked up, and contact 9 closed, a path of current is provided from transformer coil 1 through line wire, contact 2, to the middle of resistance R at 3. Here the current divides equally into the two rails and proceeds through paths 4—6, and 5—7 to R', where it reunites at 8, passes through contact 9, and back to transformer at 10.

Interference with the signalling track circuits at present in use is avoided by means of the resistances R and R' which are of a high enough value to have a negligible shunting effect on the signalling track circuit. The imposed circuit voltage may be,

and preferably is, from 5 to 20 times that of the signalling track circuit voltage. Hence the resistances R and R' have a negligible effect upon the imposed circuits.

It will be understood that the track wiring is described as an example of any suitable form which may be used.

Figure 2 represents the circuits of the primary relay on the engine. Due to the small amount of energy received through the wheels, a separately excited relay is preferable, as being a much more rugged instrument. The invention, however, is not limited in all respects to the use of a separately excited relay of the form shown.

Two relay units connected in multiple as shown are employed. S and S' are the secondary coils of these units, supplying the most of the torque, and energized from a suitable source on the engine, as described later. P and P' are the primary coils, energized through the wheels by any of the various connections already described heretofore in the Clifford applications. Both primary and secondary are energized by A. C. of approximately the same frequency, and contacts K and K' are made when currents in the primary and secondary circuits are not in phase. If either circuit, primary or secondary, is unenergized, contacts K and K' are broken.

The reason for the duplication of relays now will be clear. They are dependent upon their motion to close their respective contacts when the primary and secondary circuits are out of phase. To obviate the difficulties of synchronizing primaries and secondaries, since they are derived from entirely independent sources, the two secondaries S and S' are suitably connected by means of capacitances and reactances C and C' and L and L' so that they are in quadrature with each other. This insures that when the primaries P and P' are energized, one of the two contacts K and K' will be closed.

The local supply of A. C. for the secondaries may be obtained from any suitable source. A small turbo-generator operated from the steam mains on the engine, governor controlled to give the proper frequency, may be used. Or, as shown in the drawing, a small synchronous converter, inverted, operated by the engine storage battery, may be used. This perhaps represents

the ideal form, since it is, when once connected, readily adjustable to proper speed. A mechanical rectifier of suitable construction may also be used.

5 There is no necessity that the frequencies of the current in the primary and secondary be the same, but better operation prevails when said currents are of the same frequency. Contacts K and K' may be placed in 10 the brake solenoid controlling circuits as desired.

It will be understood that the vehicle will have thereon means for causing the stopping of the train when both the primary relays 15 have their contacts open; or signal means for indicating restrictive conditions ahead when said primary relays both have their contacts open; or both stopping and signalling means may be employed to operate 20 conjointly and controlled in a like manner by the primary relays; and whether either one or both are energized, if either or both their contacts are closed an indication will result 25 of the conditions ahead, either by the operation or non-operation of the stopping means or the existence or non-existence of the signals, the system like that of Clifford being one of continuous control. The wires O and 30 X will connect up with the various appliances necessary to carry out the Clifford system, all operated by direct current, such as the various relays and the brake controlling solenoid of that system.

It will be understood that the description 35 and diagrams are illustrative of the invention and are not to be regarded as restrictive upon the scope thereof which is defined by the accompanying claims.

I claim:

40 1. In train control apparatus, the combination of means for imposing an alternating current upon the traffic rail system of an occupied block under clear traffic conditions ahead and removing said alternating current 45 from said occupied block under restrictive traffic conditions ahead, and primary relay means on the vehicle in a conductor receiving alternating current from the energized traffic rail system of a block due to the drop in potential between the points of contact of said conductor with said rail system, and means on the vehicle controlled by said primary relay when energized to give an indication for proceeding under clear traffic 50 conditions ahead and an indication for stopping under restrictive conditions ahead, said primary relay being excited by means on the

vehicle, in addition to its excitation through said conductor substantially as described.

2. In combination in train control apparatus, means for imposing an alternating current upon the traffic rail system of an occupied block with clear conditions ahead, a primary relay on the vehicle in a conductor receiving said alternating current from the 60 said rail system due to the drop in potential between the points of contact of said conductor therewith, said primary relay being in duplicate units and each unit including a primary coil in the said conductor connected 65 therewith in multiple and each unit including also a secondary coil, said secondary coils being energized by alternating currents out of phase with each other, each unit also including a contact which is closed when the 70 primary and secondary coils belonging thereto are energized by currents out of phase, and each contact opening when the primary coil belonging thereto is deenergized, and a circuit controlled by said relay units, either 75 unit when closed maintaining a proceed indication and when both are open giving a stop indication through means in said circuit, substantially as described.

3. In combination in train control apparatus, means for imposing an alternating current upon the traffic rail system of an occupied block with clear conditions ahead, a primary relay on the vehicle in a conductor receiving said alternating current from 80 the said rail system due to the drop in potential between the points of contact of said conductor therewith, said primary relay being in duplicate units and each unit including a primary coil in the said conductor connected 85 therewith in multiple and each unit including also a secondary coil, said secondary coils being energized by alternating currents out of phase with each other, each unit also including a contact which is closed when the primary and secondary coils belonging thereto are energized by currents out of phase, and each contact opening when the primary coil belonging thereto is deenergized, and a circuit controlled by said relay 90 units, either unit when closed maintaining a proceed indication and when both are open giving a stop indication through means in said circuit, substantially as described.

4. In testimony whereof, I affix my signature.

ANDREW LANGDON.
